CONTROLLING DEVICE

George H. Fuehrer, Phillipsburg, N. J., assignor to
 Ingersoll-Rand Company, New York, N. Y., a
 corporation of New Jersey

Application October 11, 1941, Serial No. 414,561

3 Claims. (Cl. 188—81)

This invention relates to controlling devices, and more particularly to a controlling device for a rotatable member.

One object of the invention is to prevent unauthorized rotation of the rotary member.

Another object is to selectively control the direction of rotation of the rotatable member.

Other objects will be in part obvious and in part pointed out hereinafter.

In the drawings accompanying this specification and in which similar reference numerals refer to similar parts,

Figure 1 is a longitudinal side view of a rock drilling mechanism having the invention applied thereto,

Figure 2 is a longitudinal elevation, partly in section, of the controlling device,

Figure 3 is a transverse view taken through Figure 2 on the line 3—3,

Figure 4 is a plan view, in section, taken through Figure 3 on the line 4—4, and

Figures 5, 6 and 7 are transverse views taken through Figure 2 on the lines 5—5, 6—6 and 7—7, respectively.

Referring more particularly to the drawings, the invention is shown embodied in a drilling mechanism comprising a rock drill 20 having a hammer piston 19 for actuating a working implement 21, a shell 22 serving as a guide for the rock drill and a feed controlling device 23 at the rearward end of the shell 22 for determining the direction of movement of the rock drill 20 with respect to the shell. The rock drill 20 and the shell 22 may be of well known types having, respectively, ribs 24 and guideways 25 to slidably receive the ribs 24.

The feed controlling device 23 is connected to the end of the shell by bolts 26. It comprises a casing 27 having end heads 28 and 29, the latter acting as a bearing for the rearward portion of a screw 30 that is threadedly connected with the rock drill 20 and supported at its front end, in a well known manner, by the shell 22. The threaded connection between the screw 30 and the rock drill may be of a well known type where in the threads are so inclined that the screw will be caused to rotate by the movement of the rock drill 20 relatively to the shell 22.

As a preferred arrangement the screw 30 is provided with an enlarged bearing portion 31 and a bushing 32 is disposed in the head 29 to serve as a renewable bearing for the enlarged portion 31.

The portion of the screw 30 immediately rearwardly of the enlarged bearing portion 31 is in

the form of a tapered shank 33 having a threaded stem 34 that extends into a cavity 35 in the head 28. The tapered shank 33 carries a pair of flanges 36 and 37 that lie, respectively, adjacent the heads 29 and 28 and are secured upon the shank 33 by a nut 38 threaded upon the stem 34 to act against an extension 39 on the flange 37. The flanges 36 and 37 abut each other so that the force of the nut 38 will be transmitted through the flange 37 to the flange 36 for securing the latter to the shank 33.

The flanges 36 and 37 are of the same external diameter and on their peripheral surfaces 40 are arranged, respectively, rings 41 and 42 that are rotatable upon the flanges and are serrated internally and externally to provide teeth 43 and 44. In effect, the rings 41 and 42 constitute abutments to determine the direction in which the screw 30 may rotate to assure movement of the rock drill 20 in either a forwardly or a rearwardly direction along the shell 22. The means provided for interlocking engagement with the screw and the rings are shown as being in the form of pawls 45 and 46 arranged, respectively, 20 in the flanges 36 and 37. The pawls which may be of identical form are of the well known type comprising a trunnion 47 journaled in a bore 48 in the flanges and having a wing 49 extending through a recess 50, in the periphery of the 25 flange, for engagement at its free end with the teeth 43 of the rings. The pawls 45 and 46 extend in different directions and are constantly urged outwardly for engagement with the teeth 43 by spring-pressed plungers 51 arranged in 30 the flanges to engage the wings 49.

Although, as stated, the rings 41 and 42 are free to rotate within the casing 27, it is essential that, during certain conditions of operation of the device, they be held stationary in order that 40 they may serve their function as immovable abutments for the pawls 45 and 46. The means provided for thus locking the rings in a fixed position in the casing consists of a pair of locking members 52 and 53 arranged within a bore 45 54 that lies in parallelism with the axis of the casing and communicates at one side thereof with the interior of the casing. The locking members 52 and 53 are rotatable within the bore 54. They are of partly annular shape and their outer surfaces 55 engage slidably the wall of the bore 54 to centralize the locking members with respect to the bore.

The locking members are similar in all respects but are so arranged within the bore 54 that their key or locking ends 56, adapted for engagement

with the teeth 44 of the rings, lie in opposite sides of the bore 54. Thus, the locking end 56 of the locking member 52 lies on the left hand side of the bore 54 and the corresponding portion of the locking member 53 lies on the right hand side of the bore 54, as Figures 1 and 2 are viewed from the right hand end of the drawings, for engagement, respectively, with the teeth 44 of the rings 41 and 42.

In order that the locking members 52 and 53 may be constantly urged rotatably in a direction for engagement with the rings said locking members are provided at their opposed ends with wings 57 that lie in the same transverse plane and a spring 58, of the coil type, is interposed between them to rotate the locking members toward their ring-locking positions.

Means are provided for selectively moving the locking members out of engagement with the teeth 44. To this end a manually operable rod 59 is extended axially through the locking members to seat at its front end in a socket 60 in the casing 27 and at its opposite end in a bore 61 in the head 28. On the portions of the rod 59 lying in the transverse planes of the locking members 52 and 53 are wings 62 and 63 that extend in different directions for engagement with the locking ends 56 for rocking the locking members out of engagement with the teeth 44. A stem 64 on the rod 59 lies exteriorly of the head 28 and carries a lever 65 whereby the rod 59 may be rotated to its different controlling positions. The lever is secured to the stem by a nut 66.

Means are provided for locking the rod 59 in its different controlling positions. To this end a series of ribs, designated 67, 68 and 69, are formed longitudinally along the surface of an enlarged portion 70 of the rod 59 lying in the side of the head 28. The ribs 67 and 69 are suitably located to correspond with the positions of the wings 62 and 63, respectively, on the rod 59.

The rib 68 lies intermediate the ribs 67 and 69 and diametrically opposite thereof and on the enlarged portion 70 is a bearing surface 71 that engages the surface of the bore 54. The grooves or spaces 72 located on opposite sides of the ribs 67, 68 and 69 form seating surfaces for a latch 73 reciprocable on a rod 74 which is pivotally mounted on its lower end upon a pin 75 seated in the head 28. A spring 76 encircling the rod 74 acts against the latch 73 to press it constantly against the enlarged portion 70.

As a preferred arrangement, the latch 73 is provided with a notch 77 across its end surface to receive the ribs 67, 68 and 69 and to define wings 78 on the end of the latch for engagement with the side surfaces 79 of the ribs for holding the rod 59 immovable in a desired position. In order to prevent rotation of the latch 73 about its axis said latch is preferably of substantially rectangular cross sectional form and of only slightly smaller dimensions than the space it occupies in the head 28. Thus, the latch may reciprocate freely upon the rod 74 for engagement and disengagement with the ribs but will be prevented from rotating about its axis.

In the operation of the device and with the locking member 52 in locking engagement with the ring 41 and the locking member 53 disengaged from the ring 42 a stationary abutment will be provided for the pawl 45. During the ensuing operation of the rock drill 20 the jars occasioned by the reversal of the piston 19 at the forward end of its stroke and imparted to the rock drill will move the rock drill forwardly and

rotate the screw 30 through a partial revolution and the pawl 45 will thus be carried to a new position on the inner surface of the ring 41 for engagement with a tooth 43. The screw 30 will then be held against rotation to resist rearward movement of the rock drill upon the reversal of the piston 19 at the end of its rearward stroke. In this way the rock drill will gradually advance toward the work in accordance with the penetration of the working implement 21 thereinto.

When the rock drill 20 reaches the forward limit of its travel along the shell 22 the rod 59 is rotated to a position in which the rib 67 lies within the notch 77. This movement of the rod will move the locking member 52 out of engagement with the ring 41 and carry the locking member 53 into engagement with the ring 42. The screw 30 is then free to rotate in an opposite hand direction and will be rotated thus each time the piston 19 applies a jar to the rock drill 20 upon reversal of the piston at the rearward end of its stroke. Upon each revolution of the screw 30 the pawl 46 will be carried to a new position on the inner surface of the ring 42 to resist reverse rotation of the screw 30 at the instant of reversal of the piston 19 at the end of its forward stroke. Continued operation of the hammer piston 19 will cause the rock drill to be retracted to the rearward end of the shell in readiness for another run of drilling.

In the event that it be desired to restrain the rock drill against movement along the shell 22, as when starting a new drill hole, the rod 59 is rotated to a position in which the rib 68 lies within the notch 77. In this position of the rod 59 the rings 62 and 63 on the rod will be removed from the paths of movement of the locking ends 56 of the locking members. The spring 58 will then rotate both locking members into locking engagement with the rings to hold them stationary and, inasmuch as the pawls 45 and 46 are also interlocked with their respective rings the screw 30 will be held stationary and the rock drill will then remain immovable on the shell 22, unaffected by the jars imparted to it by the hammer piston.

I claim:

1. A controlling device, comprising a casing, a pair of rings rotatable in the casing and having teeth on their inner surfaces, a rotary member in the casing and the rings, separate rotary locking members of partly annular shape in the casing for each ring, means acting constantly to force the locking members into locking engagement with the rings, manually operable means extending through the locking members and being rotatable with respect thereto for selectively moving the locking members out of engagement with the rings, and pawls in the rotary member to cooperate with the teeth for determining the direction of rotation of the rotary member.

2. A controlling device, comprising a casing, a pair of rings rotatable in the casing and having teeth on their inner surfaces, a rotary member in the casing and the rings, separate rotary locking members of partly annular shape in the casing for each ring, a spring interposed between the locking members and acting constantly to force each locking member into locking engagement with a ring, manually operable means extending axially through the locking members and being rotatable for selectively moving the locking members out of locking engagement with the rings, and pawls in the rotary member to cooperate with

the teeth for determining the direction of rotation of the rotary member.

3. A controlling device, comprising a casing, a pair of rings rotatable in the casing and having teeth on their inner and outer surfaces, a rotary member in the casing and the rings, separate locking members of partly annular shape for each ring rotatable in the casing, a spring interposed between the locking members acting constantly to force the locking members into locking engagement with the teeth on the outer surfaces of the rings, an actuator extending axially through

the locking members movable to different positions to move one or the other of the locking members out of engagement with a ring and being movable to still another position to permit the spring to move the locking members simultaneously into locking engagement with the teeth on the outer surfaces of the rings, and pawls in the rotary member to cooperate with the teeth on the inner surfaces of the rings for determining the direction of rotation of the rotary member.

GEORGE H. FUEHRER.
